OF NEW YORK, N. Y., A CORPORATION OF NEW YORK

DESIGN FOR A BOTTLE

Application filed August 16, 1930. Serial No. 36,682. Term of patent 14 years.

To all whom it may concern:

Be it known that I, FERDINAND W. NITARDY, a citizen of the United States, residing at 2 Grace Court, Brooklyn, county of Kings, State of New York, have invented a new, original, and ornamental Design for a Bottle, of which the following is a specification, reference being had to the accompanying drawing, forming a part thereof.

In the drawing of the bottle:

Figure 1 is a front view;

Figure 2 is a side view; and

Figure 3 is a top view.

The dominant feature of the design consists in a shoulder of truncated conoidal form, merging smoothly with the neck of the bottle and meeting the sides of the bottle along more or less definite lines of demarcation, the horizontal sections of which shoulder are bounded by circles or ellipses and the vertical sections of which shoulder are bounded by steep-sloping or oblique straight lines.

I claim:

The ornamental design for a bottle substantially as shown and described.

FERDINAND W. NITARDY.
